HIGH TEMPERATURE ELASTIC FLUID
TURBINERichard Stroehlen, Berlin, Germany, assignor to
General Electric Company, a corporation of
New YorkApplication November 6, 1940, Serial No. 364,572
In Germany January 5, 1940

2 Claims. (Cl. 60—41)

The present invention relates to high temperature elastic fluid turbines, more specifically to turbine arrangements which include means for cooling the first stage bucket wheel and other elements subject to the high temperature of the operating fluid conducted to the turbine. The invention is of special significance in connection with gas turbines operated with exhaust gases from internal combustion engines at temperatures of 600° C. and above, although it is not limited thereto.

For a consideration of what I believe to be novel and my invention, attention is directed to the following description and the claims appended thereto in connection with the accompanying drawing.

In the drawing Fig. 1 illustrates a sectional view of a gas turbine embodying my invention; and Fig. 2 illustrates a modification of a part of Fig. 1.

The invention comprises a rotor 10 with a shaft 11 supported on a bearing 12. The rotor has a plurality of spaced rows of buckets 13 and is enclosed within a casing 14. High temperature gas is conducted to the rotor by means of an inlet chest or nozzle box 15 forming an annular row of nozzle partitions 16 for conducting gases from the nozzle box to the first row of bucket wheels. The gases discharged from the first row of buckets or from the first stage bucket wheel are conducted to a second row of buckets by a diaphragm or nozzle partition 17 supported on the casing. Similar diaphragms are associated with the succeeding rows of buckets.

In accordance with my invention the nozzle partitions 16 are formed with radial bores or openings 18 and a cooling ring 19 located in an opening formed by the casing is connected to the outer ends of the buckets of the first row or stage. The axial width of the cooling ring 19 is about equal to the width of the buckets and the radial width of the ring 19 in the present instance is about equal to the radial length of the buckets. The ring 19 is sealed on opposite sides to the turbine casing by means of known type of labyrinth packings 20 and 21. With this arrangement a considerable amount of heat absorbed by the first row of buckets is dissipated through the cooling ring 19. The cooling effect is further augmented according to my invention by the provision of cooling blades or ribs connected to the outer rim of the ring 19.

In the arrangement of Fig. 1 a row of impeller blades or vanes 22 is formed at the outer rim of the cooling ring 19. The blades 22 are sur-

rounded by a casing 23 supported on the inlet chest 15 and surrounding the turbine casing 14 to define channel 24. This channel is open at its right-hand end to atmosphere. Rows of 5 guide blades 25 and 26 are arranged on opposite sides of the cooling blades or vanes 22.

During operation the blades 22 force a stream of air or like cooling medium through the channel 24. The cooling air is conducted through 10 the radial openings 18 of the first stage nozzle blades 16 and discharged therefrom through a cylindrical channel 27 surrounding the bearing 12. The cooling air or like medium forced through the cooling channel 24 effects cooling of 15 the blades 22 and the cooling ring 19 and also of the first stage nozzle blades or partitions 16. The cooling air in the channel 27 reduces the transfer of heat from the nozzle box to the bearing and the rotor. Leakage of gases from 20 the first stage along the shaft is reduced by the provision of packings 28 and 29 sealing the shaft 11 to the channel 27.

In place of gaseous cooling medium liquid may be used for cooling the cooling ring. This is 25 especially possible in arrangements which do not require cooling of the nozzle or diaphragm partitions. Such an arrangement is shown in Fig. 2 in which outer ends of bucket blades 30 are connected to a cooling ring 31 corresponding to the ring 19 of Fig. 1. The sides of the cooling ring are provided with annular grooves 32 to 30 define part of a labyrinth sealing arrangement with a casing. The rim of the ring 31 is formed with a plurality of radial ribs or cooling vanes 33, in the present example projecting into a container 34 with cooling liquid 35. The container may be supported on or form part of the turbine casing. In some instances the container 34 with cooling liquid may be omitted, in which case the 35 ribs 33 and the cooling ring are cooled solely by the air coming in contact therewith.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by 50 Letters Patent of the United States is:

1. An elastic fluid turbine comprising a casing forming a nozzle box with a row of hollow nozzle partitions, a rotor having a first stage bucket wheel for receiving elastic fluid from the nozzle box, said bucket wheel having a row of buckets

with a cooling ring secured to the outer ends of the buckets, a labyrinth type packing between the cooling ring and the nozzle box, a cooling channel enclosing the ring and connected to the hollow partitions, and impeller blades secured to the outer end of the ring for forcing cooling medium through the channel and the hollow partitions.

2. An elastic fluid turbine comprising a casing forming a nozzle box with a row of hollow nozzle partitions, a rotor with a shaft having a first stage bucket wheel for receiving elastic fluid from the nozzle box, said bucket wheel having a row of radially arranged buckets with a cooling

ring secured to the outer ends of the buckets, a labyrinth type packing between the cooling ring and the nozzle box, a cooling channel enclosing the ring and connected to the outer ends of the hollow partitions, impeller blades secured to the outer end of the ring for forcing cooling medium through the channel and the hollow partitions, and another cooling channel surrounding the shaft and connected to receive cooling medium from the inner ends of the hollow partitions to reduce heat transfer from the nozzle box to the rotor.

RICHARD STROEHLIN.
